US00D773716S

(12) **United States Design Patent** (10) Patent No.: **US D773,716 S**
(45) Date of Patent: ** *Dec. 6, 2016

(54) **WALL MOUNTED LIGHT FIXTURE HAVING STRUTS**

(71) Applicant: **Hubbell Incorporated**, Shelton, CT (US)

(72) Inventor: **Robert R. Nankil**, Buena Park, CA (US)

(73) Assignee: **Hubbell Incorporated**, Shelton, CT (US)

(*) Notice: This patent is subject to a terminal disclaimer.

(**) Term: **14 Years**

(21) Appl. No.: **29/521,589**

(22) Filed: **Mar. 25, 2015**

(57) **CLAIM**

The ornamental design for a wall mounted light fixture having struts, as shown and described.

DESCRIPTION

FIG. 1 is a top perspective view of the wall mounted lighting fixture having struts showing the invention;

FIG. 2 is a top view of the lighting fixture of FIG. 1;

FIG. 3 is a front view of the lighting fixture of FIG. 1;

FIG. 4 is a right side view of the lighting fixture of FIG. 1 where the left side view is a mirror image thereof;

FIG. 5 is a rear view of the lighting fixture of FIG. 1;

FIG. 6 is a bottom perspective view of the lighting fixture of FIG. 1; and,

FIG. 7 is a bottom view of the lighting fixture of FIG. 1. The broken lines shown on the drawings depict portions of the light fixture that form no part of the claimed design.

1 Claim, 2 Drawing Sheets
